UNITED STATES PATENT OFFICE

MORRIS COHEN, OF BROOKLYN, NEW YORK, ASSIGNOR TO THE GIFT HOUSE, INC., OF NEW YORK, N. Y., A CORPORATION OF NEW YORK

DESIGN FOR A COMBINED ASH RECEIVER AND CIGARETTE AND MATCH HOLDER

Application filed July 17, 1929. Serial No. 32,091. Term of patent 3½ years.

To all whom it may concern:

Be it known that I, MORRIS COHEN, a citizen of the United States, residing at 4701 15th Avenue, Brooklyn, New York city, in the county of Kings and State of New York, have invented a new, original, and ornamental Design for a Combined Ash Receiver and Cigarette and Match Holder, of which the following is a specification, reference being had to the accompanying photograph, forming part thereof.

The figure is a front perspective view of a combined ash receiver and cigarette and match holder, showing my new design.

I claim:

The ornamental design for a combined ash receiver and cigarette and match holder, as shown.

MORRIS COHEN.
